UNITED STATES PATENT OFFICE.

WILLIAM JENKINS DAWSON, OF LAWRENCE, KANSAS.

CAR-COUPING.

SPECIFICATION forming part of Letters Patent No. 264,634, dated September 19, 1882.

Application filed February 7, 1882. (No model.)

To all whom it may concern:

Be it known that I, WM. JENKINS DAWSON, of Lawrence, in the county of Douglas and State of Kansas, have invented a new and Improved Car-Coupling; and I do hereby declare that the following is a full, clear, and exact description of the same, reference being had to the accompanying drawings, forming part of this specification, in which—

10 Figure 1 is a perspective view of my improved car-coupling. Fig. 2 is a central vertical section of the same; and Fig. 3 is a top view with the cover of box open, showing devices for supporting coupling-pin in position 15 for automatic coupling.

15 My invention relates to improvements in car-couplings; and it consists in the peculiar construction and arrangement of the parts, as hereinafter more fully set forth.

20 In the accompanying drawings, *a* represents a draw-head of the usual construction, the upper face of which is provided with the longitudinal ribs *b b*, secured thereto.

25 *c* represents a transverse piece, connecting the rear ends of the ribs *b* and secured thereto, forming a box or receptacle, *b'*, on the upper face of the draw-head, open at its top.

30 *d* represents a cover for the open top of said box, the rear end of said cover being hinged to the ribs *b b* by means of the eye-plates *e e*, secured to the upper face of the cover *d* near its rear end, and rod or pintle *f*, passing through the eyes of the eye-plates *e* and corresponding holes made in the ribs *b*.

35 *g* represents an orifice made in the cover for the passage of the coupling-pin *i*.

40 *h h'* represent hollow flanges or cylinders, secured to the upper and lower faces of the cover, over and under the orifice *g*, to guide the coupling-pin *i* in its movements.

45 *k k'* represent two elbow-levers, each pivoted by pins *k² k³* to the upper face of the draw-head, and passing through slots *k⁶* in the ribs *b*, and terminating in handles *k⁷*, and having the semi-circular arms *k⁵*, provided with straight edges adapted to close when the elbow-levers are moved in one direction, and close the orifice *g'* in the top face of the draw-head and support the coupling-pin, and when the elbow-levers are moved in the opposite direction to

open and allow the coupling-pin to pass down into the draw-head and through the link *e*.

50 *k⁸ k⁹* represent pins passing through the semicircular heads of the arms *k⁵*, the lower ends of which bear against the upper face of the draw-head to prevent the lower faces of the arms *k⁵* from resting on the upper face of the draw-head and allow the escape of water through the orifice *g'*. The rear end of the arm *k⁵* is provided with a downwardly-projecting pin, *k⁹*, which engages with a curved slot, *k¹⁰*, in the rear end of the other arm, *k*, so that any motion imparted to one of the arms *k⁵* will impart a similar motion to the other.

55 *m m* represent rods attached to the arms *k⁴* of the elbow-levers outside the draw-head, thence curved downwardly, with their outer ends passing through holes in the flange at the mouth of the draw head, and projecting slightly beyond said flange, for a purpose 60 hereinafter set forth.

65 *n* represents a yoke or bail provided with parallel vertical eye-rods *n'*, by means of which the bail is pivoted to the outside and upper part of the draw-head by pins *n''*, whereby a 70 swinging motion can be imparted to the bail to and from the mouth of the draw-head, to raise and lower the link when cars of different heights are to be coupled, by means of the levers *n²*, secured to the bail.

75 *o* represents the lower horizontal transverse rod or bar of the yoke, adapted in the swinging movement of the bail to pass under the mouth of the draw-head.

80 *o'* represents a rod or bar parallel to the rod *o*, and secured at its ends to the vertical eye-rods *n'*, and adapted, when the rods *n'* are vertical, to lie in a horizontal groove in the face of the draw-head.

85 In coupling cars of different height, the coupling-pin having been inserted through the link in the lowest draw-head, the bail in said draw-head is raised by the lever *n²*, raising the link so as to enter the opening in the opposite higher draw-head. If one draw-head were 90 much higher than the other, with an ordinary bail having but one lower transverse rod, the tendency would be, in coupling the cars, if said rod were raised as high as the points of suspension of the bail to break said bail by 95 100

the impact of the draw-heads, or to throw over backward the bail and prevent the coupling of the cars.

By constructing my bail with two horizontal parallel cross-bars, $o\ o'$, the former supporting the outer end of the link, the rod o' first comes in contact with the opposite draw-head, always below the points of suspension of the bail, and insures the downward movement of the bail. In coupling cars of different heights, should the bail be raised above its points of suspension, $p\ p'$ represent springs coiled around the inner ends of the pins n' , which suspend the bail, the opposite ends of said springs bearing against the bail or handle, the function of the springs $p\ p'$ being to force the bail down when raised by the levers.

The above construction of bail may be applied to the inside of the draw-head, as well as the outside, with slight differences in the details of construction, without departing from the spirit of my invention.

To hold the link horizontal in a draw-head, with cars of the same height, I employ a spring-dog, r , hung on the transverse rod r' , secured to the opposite sides of the draw-head. The dog r is composed of the two curved arms $r''\ r^2$, the latter bearing on the inner face of the top of the draw-head, and the former, r'' , pressing against the upper face of the rear end of the link and holding the latter horizontal in coupling the cars.

What I claim as new, and desire to secure by Letters Patent, is—

1. The combination, with the box b' on the upper face of the draw-head, provided with the hinged cover d , having orifice g' and guide-flanges $h\ h'$, and coupling-pin i , of the elbow-

levers $k\ k'$, jointed together, pivoted to the upper face of the draw-head, and provided near their outer ends with the rods $m\ m$, passing through holes in the flanged face of the draw-head, substantially as described. 40

2. The combination, with draw-head a , provided with holes in its upper and lower face 45 for the passage of the coupling-pin, of the elbow-levers $k\ k'$, pivoted to the upper face of the draw-head and jointed to each other by the pin k^9 and slot k^{10} , handles k^7 , arms k^5 , semicircular at their outer ends, and provided 50 with the pins k^8 , and rods $m\ m$, passing through holes in the flanged face of the draw-head, substantially as described.

3. The combination, with a draw-head, of the bail n , pivoted thereto and provided with 55 the horizontal bars $o\ o'$, and levers n^2 , substantially as described, and for the purpose set forth.

4. The combination, with a draw-head and bail, n , pivoted thereto, and provided with the horizontal bars $o\ o'$, and levers n^2 , of the springs 60 $p\ p'$, substantially as described, and for the purpose set forth.

5. The combination, with a draw-head, a , and a link, l , of the spring-dog r , pivoted on a transverse rod secured to the opposite sides 65 of the opening in the draw-head, and composed of the two arms $r''\ r^2$, the latter, r^2 , bearing on the inner face of the top of the draw-head, and the former, r'' , pressing against the upper face of the rear end of the link and holding it horizontal, substantially as described. 70
